UNITED STATES PATENT OFFICE.

EDWIN G. ADAMS, OF NEAR PLAIN CITY, OHIO.

DUST-RECEPTACLE.

No. 899,937.

Specification of Letters Patent. Patented Sept. 29, 1908.

Application filed June 9, 1906. Serial No. 321,052.

To all whom it may concern:

Be it known that I, EDWIN G. ADAMS, a citizen of the United States, residing near Plain City, in the county of Union and State of Ohio, have invented new and useful Improvements in Dust-Receptacles, of which the following is a specification.

My invention relates to dust receptacles, and its primary object is to provide a device 10 of this character which is adapted to be let through an opening in a floor to position its entrance in alinement therewith, whereby the sweepings of a room may be readily and quickly directed therein.

15 A further object of my invention is to provide a device of the character stated from which the sweepings may readily and quickly be moved, which is simple, durable and efficient, and which may be manufactured and 20 sold at a comparatively low cost.

With the above and other objects in view, the invention consists in the construction, combination and arrangement of parts hereinafter fully described, claimed and illustrated in the accompanying drawing, 25 wherein:

Figure 1 is a perspective view of a dust receptacle constructed in accordance with my invention, and Fig. 2 is a vertical central section therethrough.

Referring to the drawing by reference numerals, 2 designates the front, 2^a the side and 3 the rear walls of an open-ended receptacle. The receptacle is adapted to be let 35 through an opening in a floor to position its upper open end or entrance in alinement therewith, whereby the sweepings of a room may readily and quickly be directed therein. The rear wall 3 is continued upward above 40 the front and side walls 2 and 2^a, respectively, and thence horizontally in the direction of the front wall to provide a hood 3^a, which overhangs the entrance to the receptacle and directs the sweepings therein. 45 The horizontal portion of the hood 3^a is supported and braced by side flanges 3^b. The front edges of the flanges 3^b are inclined rearwardly and downwardly to leave the upper end of the receptacle open at its front and 50 sides. It should be thus apparent that the hood 3^a is of such construction that it will not interfere with the directing of the sweepings into the receptacle, and that it will deflect the sweepings therein.

A horizontally disposed flange 4, which is 55 secured to the upper edges of the front and side walls of the receptacle, is adapted to be let into the floor to support the receptacle in applied position. A cover 5 is hingedly secured to the horizontal portion of the hood 60 3^a, as at 6, and is adapted to fully close the entrance to the receptacle. An arm 7 is secured to and projects laterally from one end of the cover 5 and provides means by which the cover may be swung into opened position. The cover may be swung into opened position by exerting an upward pressure upon the arm 7 by means of the foot. If found desirable, however, a chain may be provided for raising the cover, and in this 70 instance one end of the chain should be secured to the arm 7 and its other end secured at an elevation to adapt it to be readily and quickly grasped. The lower ends of the front and rear walls of the receptacle are 75 formed to provide inwardly directed and horizontally disposed flanges 8, upon which a closure 9 is slidably mounted. To permit the closure 9 to be removed and applied, the lower portion of one of the side walls of the 80 receptacle is cut away, as fully disclosed in Fig. 1 of the drawing.

From the foregoing description, taken in connection with the accompanying drawing, the construction and mode of operation of 85 the invention should be understood without a further extended description.

Changes in the form, proportions and minor details of construction may be made within the scope of the claims without departing from the spirit or sacrificing any of 90 the advantages of the invention.

Having fully described and illustrated my invention, what I claim is:

A device of this character described comprising a receptacle open at top and bottom and provided at its upper end around its front and sides with outwardly extending supporting flanges and at its lower end with inwardly extending front and rear flanges, a hood partially overhanging the open top of the receptacle and embodying a top wall, a back wall integral with the rear wall of the receptacle body and triangular side walls having their front edges inclining downwardly and rearwardly from the forward edge of said top wall, an inclined cover plate pivoted at its upper edge to the top of the hood and adapt- 95 100 105

ed to rest at its lower edge upon the front supporting flange, said cover being provided with triangular end walls to rest upon the side supporting flanges and against the inclined edges of the end walls of the hood, a handle applied to one of the end walls of the cover and extending laterally therefrom, and a sliding closure supported by the flanges at

the lower end of the receptacle body for withdrawal at one side of said body.

In testimony whereof, I affix my signature in presence of two witnesses.
